UNITED STATES PATENT OFFICE

PETER S. ECKLAND, OF MINNEAPOLIS, MINNESOTA

AUXILIARY SEAT FOR BUSES AND THE LIKE

Application filed March 8, 1929. Serial No. 345,320.

This invention relates to auxiliary seats for use particularly in busses, railroad cars, street cars, theaters and churches.

In busses, railroad cars, theaters and churches, it is often desirable to seat passengers or guests in the aisles, in order that additional seating capacity may be afforded. At the present time, folding camp stools are largely used in busses to seat passengers in the aisle of a bus when the same is overcrowded. Camp stools are unsatisfactory, inasmuch as they cannot be readily extended for use or folded up in a crowded bus and they are always in the way of passengers walking through the aisle.

It is the main object of this invention, therefore, to provide a novel and improved auxiliary seat construction which, although particularly designed for use in busses, can be utilized elsewhere as an auxiliary seat and which can be mounted on a suitable support and can be readily extended for use to project outwardly from its support as into an aisle, and which when its use is discontinued, will automatically fold up in out-of-the-way position adjacent its support.

To this end, the invention consists in the novel parts and novel combinations of parts hereinafter defined in the claims, and described in the following specification, made in connection with the accompanying drawings, wherein like reference characters refer to the same or similar parts throughout the various views, and, in which,

Fig. 1 is a view in rear elevation of the auxiliary seat of the present invention applied to the frame of a main bus seat, the auxiliary seat being shown in extended position in full lines and being shown in folded out-of-the-way position in dotted lines;

Fig. 2 is a view in side elevation of the auxiliary seat in extended position;

Fig. 3 is a vertical section taken on the line 3—3 of Fig. 1, as is indicated by the arrows;

Fig. 4 is a vertical section taken on the line 4—4 of Fig. 3, as is indicated by the arrows;

Fig. 5 is a horizontal section taken on the line 5—5 of Fig. 3, as is indicated by the arrows, and

Fig. 6 is a horizontal section taken on the line 6—6 of Fig. 3, as is indicated by the arrows.

Referring to the drawings, an aisle side frame A for a main bus seat is illustrated, and although practically any suitable vertical support can be substituted for the side frame A, the side frame is illustrated as being particularly constructed for the accommodation of the auxiliary seat. The side frame A, as shown, is formed in a single casting and consists essentially of two vertical legs 7 and 8, a horizontal top cross bar 9 connecting the upper ends of the two legs 7 and 8 and forming the aisle arm of the main seat of the bus, a horizontal cross bar 10 connecting the medial portions of the legs 7 and 8 and a horizontal angle bar 11 connecting the legs 7 and 8 adjacent to but spaced from the lower ends of the legs. The legs 7 and 8 are of channel shape and are preferably provided with ribs 7^a and 8^a respectively, which project outwardly at their outer sides. The top cross bar 9 is also preferably of channel shape, the open portion of the channel projecting downwardly and the outer flange of the channel being cut away at 9^a and 9^b, for the purposes hereinafter described. The cross bar 10 is preferably constructed of angular shape and is provided with a wide inwardly extending horizontal flange 10^a forming a support for a spring and cushion support frame 12, for the main bus seat, the frame 12 having the cross bar 12^a at its central portion. The inner flange of the cross bar 9, and the vertical flange of the cross bar 10, lie in the same plane and are joined by vertical strips 13 formed integral with the inner flanges of the legs 7 and 8, to comprise, in reality, an open frame. The lower angle bar 11 is preferably secured to the inner sides of the legs 7 and 8 and, accordingly, will be inwardly spaced slightly from the plane of the frame above described. A hub 14 projects rearwardly from the rear leg 8 and the back of the main seat (not illustrated) is adapted to be secured to this hub.

In accordance with the present invention, a pair of horizontally spaced cap bearings 15

75

80

85

90

95

100

are secured to the inner vertical flange of the top cross bar 9, and a horizontal shaft 16 is journaled in these two bearings and held from lengthwise movement thereby. The 5 bearings 15 are preferably placed on the cross bar 9 immediately behind the cut-away portions 9^a on the outer side flange of the cross bar and the purpose of cutting away the flange is to permit the caps of the bearings 10 to be easily secured in place. An auxiliary seat bottom 17 is provided and carries spaced lugs 17^a at its inner edge which are journaled on the shaft 16. Upwardly extending lugs 17^b are provided on the rear edge of the seat 15 bottom 17 and a shaft 18 is journaled in the lugs 17^b. A rectangular seat back 19 carrying a back cushion 20, has downwardly projecting lugs 19^a fixed to the shaft 18, and a coiled spring 21 surrounding the central portion 20 of the shaft 18 and fixed at one end to the seat bottom 17 and bearing at its other end against the rear portion of the seat back 19, normally acts to hold the seat back 19 folded downwardly against the seat bottom 17. The 25 shaft 18 projects inwardly from the seat frame 19 through the cut-away portion 9^b in the outer flange of the top cross bar 9 for some little distance, and a cam 22 is carried at this end of the shaft 18, so that the cam will extend within the outline of the side frame A at the point of jointure between the leg 8 and the cross bar 9. A vertical sliding rod 23 is mounted within the leg 8, projects through a partition 24 in the leg and has a reduced upper portion 23^a fitting within a vertical opening 9^c in the top cross bar 9. The rod 23 carries on its reduced portion 23^a, an arm 25 which projects above the cam 22 and is adapted to be acted on by the cam as the back 19 of the auxiliary seat is swung downwardly 30 against the bottom 17 to raise the rod 23. A coiled spring 26 fitting about the lower portion of the rod 23 re-acts between the partition 24 and a short cross pin 27 carried by the rod 23 adjacent its lower end. The rod 23 is pivoted at its lower end to the rear end of an arm 28 pivoted adjacent its central portion on a pivot 29, mounted in a hub 11^a on the angle bar 11. The rear end of the arm 28 is preferably offset outwardly from the main portion 40 of the arm, as best shown in Fig. 6. In order that the central portion of the arm may fit within the channel of the leg 8 and the rear end of the arm is bent in U-shape, as shown, so that the pivot 30 joining the lower end of the rod 23 to the rear end of the arm 28, may have a two point support in the arm. The forward end of the arm 28 is provided with an upwardly projecting tooth portion 28^a 45 adapted to be engaged in a notch 31^a, formed on the lower edge of the lower and inner end of a supporting bar 31, pivoted at its upper end to a pair of ears 32 formed on and projecting downwardly from the lower outer portion of the seat bottom 17. When the

seat bottom 17 is swung outwardly to horizontal position as is illustrated in full lines Fig. 1, from the side frame A, the supporting bar 31 will project diagonally downwardly to the angle bar 11, and the lower and inner portion of the supporting bar will be bent relative to the main portion of the bar, so that the lower portion extends substantially horizontally and rests on the horizontal flange of the angle bar 11 with the tooth portion 28^a of arm 28 in engagement with the notch 31^a. The extreme lower and inner end of the supporting bar 31 projects through a keeper 33 secured to, or formed integral with the angle bar 11. This keeper 33 forms the outer support for a casing within which the support bar 31 may be carried when the auxiliary seat is lowered. The said casing consists of two side plates 34 held in spaced relation from each other by a lower block 35, an upper strip 36 and an upper and inner block 37 secured to the central cross bar of the spring and cushion support frame 12 of the main seat. It will be noted that the inner portions of the plates 34 project diagonally upwardly and that the inner block 37 is cut diagonally away at 37^a on its lower edge slightly outwardly from the extreme innermost edges of the plates 34. A block 38 is mounted between the plates 34 at the lower edges thereof at the point where the plates first start to extend diagonally and a bar spring 39 is secured at its forward end to this block 38 so that the main and free portion of the spring projects inwardly and diagonally upwardly. 50

Operation

Let us consider that the auxiliary seat is swung to the position illustrated in Fig. 1, and that the seat is occupied by a passenger. 55 When the passenger gets up from the seat, the spring 21 will force the back 19 to swing downwardly and fold against the seat bottom 17. During this action, the shaft 18 and cam 22 secured thereto will be rotated, thereby forcing the cam to engage the arm 25 on the rod 23 to slide the rod 23 upwardly against the tension of the spring 26. As the rod 23 slides upwardly, the rear end of arm 28 will be carried upwardly thereby swinging the forward or tooth portion of the arm 28^a downwardly and out of engagement with the notch 31^a in the support bar 31. Prior to this time, the tooth portion 28^a of arm 28 will have held supporting bar 31 in diagonal outwardly extending relation to support the seat bottom 17 in horizontal position. Upon the disengagement of the tooth portion 28^a from the notch 31^a of support arm 31, the seat bottom 17, seat back 19 and other parts carried thereby, will be free to swing downwardly and they will, in fact, fall by gravity downwardly, swinging about the shaft 16 as an axis, until the seat bottom 17 strikes the frame formed by the vertical inner 60

flange of the top cross bar 9, the strips 13 and the vertical flange of the cross bar 10, whereupon the seat bottom 17 and seat back 19 will depend downwardly from the shaft 16 in substantially vertical position and will be disposed completely within the outline of the side frame A, as shown in dotted lines Fig. 1. As the seat bottom 17 swings downwardly, the supporting bar 31 will slide inwardly, through the keeper 33 into the casing formed by the plates 34, block 35, strip 36 and block 37. During this movement of the supporting bar, the inner and lower end of the bar will strike the bar spring 39, which will cause the said end of the bar to move upwardly against the surface 37^a on the block 37, as shown in dotted lines, Fig. 1, whereupon the spring 39 will hold the said portion of the bar tightly against the surface 37^a to prevent the bar from rattling during the travel of the bus. It will thus be seen that when a passenger gets up from the auxiliary seat, after using the same, the seat will automatically of its own accord, fold up and swing downwardly in out-of-the-way position within the outline of the side frame A. The aisle into which the seat will project when the seat is in extended position, will thus be quickly cleared for the free passage of passengers from front to rear through the bus.

When it is desired to set up the seat, from the position of the seat within the outline of the side frame A, the lower edge of the seat back 19, or seat bottom 17, will be grasped and the seat bottom 17 will be swung upwardly to horizontal position projecting outwardly from the side frame. The back 19 will then be raised against the tension of spring 21 until the back is in an approximately vertical position. This movement of the back will cause the shaft 18 and cam 22 to be revolved, thereby permitting the spring 26 to act to slide the rod 23 and arm 25 carried thereby downwardly. The rear end of the arm 28 will, accordingly swing downwardly, whereupon the tooth portion 28^a of the arm 28, will be swung upwardly and into engagement with the notch 31^a in the supporting bar 31. The auxiliary seat will then be held in extended position until the seat back 19 is again allowed to fold downwardly on the seat bottom 17. It will be noted that the lugs 19^a on the back 19 at their lower ends will abut the top surface of the seat bottom 17, to limit rearward movement of the seat back past a slight inclination beyond the vertical when the seat back is upwardly swung from the seat bottom 17.

Although the device has been described as being applied to the side frame of a bus seat, to provide an auxiliary aisle seat for the bus, it will, of course, be understood that it can be used as an auxiliary seat in railway cars, street cars, churches, theaters, or, in fact, anywhere where an auxiliary seat is desired.

The device has been amply demonstrated in actual practice and has been found to be very successful for the purposes intended. The parts are few and the construction is simple.

It will, of course, be understood that various changes may be made in the form, details, arrangement and proportions of the various parts without departing from the scope of the present invention.

What is claimed is:

1. An auxiliary seat for busses and the like, having in combination, a suitable support, a seat bottom pivoted to said support, and adapted to be swung upwardly to extend outwardly therefrom in substantially a horizontal plane, a seat back pivoted to said bottom, resilient means normally tending to fold said back downwardly against said bottom, means for supporting said bottom in outwardly extended horizontal position, and means operating when said back folds downwardly against said bottom to disengage said supporting means and permit said bottom and back to gravitate downwardly adjacent said support whereby when an occupant gets up from said seat, said seat will automatically fold up.

2. An auxiliary seat for busses and the like, having in combination, a suitable support, a seat bottom pivoted to said support and adapted to be swung outwardly therefrom to extend in substantially a horizontal plane, a seat back pivoted to said bottom and adapted to be folded downwardly against said bottom, a bar pivoted to said bottom, a member adapted to engage said bar to cause said bar to support said bottom in horizontal outwardly extended position, and means operating as said back is swung downwardly on said bottom to cause said member to be disengaged from said bar and permit said bottom and back to swing downwardly adjacent said support to substantially vertical position.

3. An auxiliary seat for busses and the like, having in combination, a suitable support, a seat bottom pivoted to said support and adapted to be swung outwardly therefrom to extend in substantially a horizontal plane, a seat back pivoted to said bottom and adapted to be folded downwardly against said bottom, a bar pivoted to said bottom, a member adapted to engage said bar to cause said bar to support said bottom in horizontal outwardly extended position, a cam carried by said back and a rod connected to said member and adapted to be engaged by said cam when said back is folded downwardly against said bottom, to operate said member and disengage the same from said bar to permit said bottom and back to swing downwardly adjacent said support.

4. The structure defined in claim 3, and resilient means normally forcing said back to fold downwardly against said bottom,

whereby after occupancy said bottom and back will be automatically swung downwardly adjacent said support.

5. An auxiliary seat for busses and the like, having in combination, a suitable support, a seat bottom pivoted to said support, and adapted to be swung upwardly and outwardly therefrom to extend in substantially a horizontal plane, a seat back pivoted to said seat bottom, resilient means normally urging said seat back to be swung downwardly against said seat bottom, a cam secured to said back, a rod slidably mounted in said support, and having an arm projecting over said cam, a supporting bar pivoted at one end to said seat bottom, an arm pivoted to said support, pivotally secured to said rod at one end and having another portion adapted to be releasably engaged with said supporting bar to hold said seat bottom in outwardly swung horizontal relation, said last mentioned arm being adapted to be disengaged from said supporting bar when said rod is actuated by said cam to slide in one direction, thereby permitting said seat bottom and back to gravitate downwardly adjacent said support to substantially vertical position.

6. The structure defined in claim 5, a keeper through which the lower end of said supporting bar projects, and a guide casing into which said supporting bar will be carried when said seat bottom is swung downwardly.

7. An auxiliary seat for busses and the like, having in combination, a suitable support, a seat bottom pivoted to said support and adapted to be swung outwardly therefrom to extend in substantially a horizontal plane, a seat back pivoted to said bottom and adapted to be folded downwardly against said bottom, a bar pivoted to said bottom, a member adapted to engage said bar to cause said bar to support said bottom in horizontal outwardly extended position, means operating as said back is swung downwardly on said bottom to cause said member to be disengaged from said bar and permit said bottom and back to swing downwardly adjacent said support to substantially vertical position, a keeper through which the lower end of said bar projects and a casing secured to said keeper into which said bar will be carried as said seat and back swing downwardly adjacent said support.

8. The structure defined in claim 7, and a spring mounted in said casing in the path of said bar as it moves into said casing and acting to yieldingly force the lower end of said bar upwardly a short distance, and a member against which the lower end of said bar will be forced by said spring, whereby said bar will be held against said last mentioned member under resilient tension to prevent the rattling thereof.

9. An auxiliary seat for busses and the like,

having in combination, a suitable support, a seat bottom pivoted to said support and adapted to be swung upwardly to extend outwardly therefrom in substantially a horizontal plane, a rod mounted at the rear edge of said bottom, a seat back pivoted on said rod, a coiled spring encircling said rod and having one end bearing against said bottom and its other end bearing against said back to urge said back to fold downwardly against said bottom, means for supporting said bottom in outwardly extended horizontal position and means operating when said back folds downwardly against said bottom to disengage said supporting means and permit said bottom and back to gravitate downwardly adjacent said support whereby, when after occupancy, an occupant rises from said seat, said seat will automatically fold up.

In testimony whereof I affix my signature. 85
PETER S. ECKLAND.
